UNITED STATES PATENT OFFICE.

HENRY L. MOREAU, OF LAKE MAHOPAC, NEW YORK.

COLLAPSIBLE-TUBE CLOSURE.

Application filed November 6, 1925. Serial No. 67,365.

To all whom it may concern:

Be it known that I, HENRY L. MOREAU, a citizen of the United States, and a resident of Lake Mahopac, in the county of 5 Putnam and State of New York, have invented a new and Improved Collapsible-Tube Closure, of which the following is a full, clear, and exact description.

This invention relates to collapsible tube 10 closures, the primary object of the invention being to provide means whereby a screw-threaded cap, constituting a closure, is limited in its movement and is prevented from accidental loss or displacement.

15 It is to be understood that while I shall describe my improved closure in connection with a collapsible tube it is obvious that the closure has a broader scope in its inventive concept as I do not wish to be limited to the 20 combination of a collapsible tube although this is its primary use.

With these and other objects in view, the invention consists in certain novel features of construction and combinations and arrangements of parts which will be more 25 fully hereinafter described and pointed out in the claims.

In the accompanying drawings—

Figure 1 is a view in longitudinal section 30 through a tube and closure cap therefor, showing the cap in its fully opened position;

Figure 2 is a similar view, showing the cap in closed position;

Figure 3 is a view, similar to Figure 1, 35 illustrating a modification.

1 represents a receptacle, which we will assume is an ordinary collapsible tube adapted to contain paste, soap or any other material 2 which can be forced or discharged 40 when the tube is collapsed. This tube 1 is formed at its outlet end with a screw-threaded plug 3, the latter having a passage 4 therethrough opening at one side of the plug and constituting an outlet for the contents of the tube.

45 5 represents a cap or closure which is internally screw-threaded as shown at 6 so as to mesh with the threads of plug 3 and adapted to be screwed downwardly to a position such as shown in Figure 2 to constitute a closure for the passage 4 and adapted also to be screwed in the opposite direction to open the passage 4, as seen in Figure 1.

50 My invention resides specifically in means 55 for limiting the movement of the closure or

cap 5 on the plug 3. In Figure 1 I illustrate as a limiting means a cord or other flexible member 7 which is secured at one end to the cap 5 and at its other end to the plug 3, and this cord or flexible device is of a length 60 which allows the cap to be moved a limited distance, as shown in Figure 1, but not far enough to be entirely removed from the plug 3, preventing any possibility of loss of the cap or closure. When the cap is screwed 65 downwardly to close the outlet the cord 7 will coil or otherwise shape itself, as indicated in Figure 2.

In the modification illustrated in Figure 3, I provide a cup-like receptacle 8 at the 70 upper end of plug 3 and form an opening 9 in the outer wall of said receptacle. In this modification I employ a flexible device such as a cord 10 which is secured to the cap 5 and which projects through the opening 9, and has on its lower end within the receptacle 8 a ball or other form of enlargement 11 which is of greater diameter than the opening 9. By reason of this construction, the flexible cord or device will move 75 through the opening 9 when the cap is screwed home and will collect or coil within the receptacle 8 and prevent the possibility of the cord becoming jammed or entangled in the screw-threaded parts.

80 Various slight changes and alterations might be made in the general form of the parts described without departing from my invention and hence I do not limit myself to the precise details set forth but consider myself at liberty to make such slight changes and alterations as fairly fall within the spirit and scope of the appended claims.

85 I claim:

1. A device of the character described, including a collapsible tube, an externally screw-threaded neck on the tube having an outlet in the side wall thereof, a screw-threaded cap meshing with the threads of 100 the neck and adapted when screwed inwardly to close the outlet, a flexible device enclosed entirely within the cap connected at its respective ends to the cap and the neck to limit the outward movement of the cap, 105 said neck having a pocket in its outer end, and an enlargement on said flexible device located in said pocket, the extremity of the neck having an opening therein for the movement of the flexible device, and said 110

socket adapted to accommodate the flexible device therein when the cover is screwed to its closing position.

2. The combination with a dispensing tube having a neck thereon and an outlet in the side of the neck, of a cap movable longitudinally of the neck and adapted to cut off the outlet when in one extreme position and uncover the outlet when in another extreme position, and a flexible device located entirely within the cap and connecting the end of the neck with the end of the cap to limit the movement of the cap in one direction.

HENRY L. MOREAU.
